(57) **CLAIM**

The ornamental design for an apparatus for recording, transmission or processing information, as shown and described.

DESCRIPTION

Cross reference is made to copending U.S. design patent application Ser. No. 29/536,724 entitled “Apparatus for Recording, Transmission or Processing of Information” by Kreeb et al., filed on even date herewith; U.S. design patent application Ser. No. 29/536,734 entitled “Apparatus for Recording, Transmission or Processing of Information” by Kreeb et al., filed on even date herewith; and U.S. design patent application Ser. No. 29/536,737 entitled “Apparatus for Recording, Transmission or Processing of Information” by Kreeb et al., filed on even date herewith.

FIG. 1 is a front perspective view of an apparatus for recording, transmission or processing information showing our new design;

FIG. 2 is a rear perspective view showing the design for the apparatus for recording, transmission or processing information of FIG. 1;

FIG. 3 is a front elevational view showing the design for the apparatus for recording, transmission or processing information of FIG. 1;

FIG. 4 is a rear elevational view showing the design for the apparatus for recording, transmission or processing information of FIG. 1;

FIG. 5 is a left side elevational view showing the design for the apparatus for recording, transmission or processing information of FIG. 1;

FIG. 6 is a right side elevational view showing the design for the apparatus for recording, transmission or processing information of FIG. 1;

FIG. 7 is a top plan view showing the design for the apparatus for recording, transmission or processing information of FIG. 1; and,
